UNITED STATES PATENT OFFICE.

CHARLES A. STUART, OF KENOSHA, WISCONSIN, ASSIGNOR TO SIMMONS COMPANY, OF NEW YORK, N. Y., A CORPORATION OF DELAWARE.

DESIGN FOR A BEDSTEAD END FRAME.

Application filed February 24, 1925. Serial No. 12,462. Term of patent 14 years.

To all whom it may concern:

Be it known that I, CHARLES A. STUART, a citizen of the United States, and a resident of the city of Kenosha, county of Kenosha, and State of Wisconsin, have invented a new, original, and ornamental Design for Bedstead End Frame, of which the following is a specification, reference being had to

the accompanying drawing, forming part thereof.

The figure is a perspective view of a bedstead end frame showing my new design.

I claim:

The ornamental design for a bedstead end frame as shown.

CHARLES A. STUART.
